CLAIM

I claim the ornamental design for a controller device for a heating kit, as shown and described.

DESCRIPTION

This application claims the benefit of the U.S. Design patent application Ser. No. 29/515,053, filed on Jan. 20, 2015, which is incorporated herein by reference.

FIG. 1 shows a top view of a controller device for a heating kit;

FIG. 2 shows a bottom view of the controller device;

FIG. 3 shows a left side view of the controller device;

FIG. 4 shows a right side view of the controller device;

FIG. 5 shows a front view of the controller device; and,

FIG. 6 shows a rear view of the controller device.

The dashed lines are for the purpose of illustrating portions of the controller device and form no part of the claimed design. The dotted lines on the surface portions indicate contour and not surface decoration.
